Des. 223,416
Patented Apr. 11, 1972

223,416

CLOTHES HANGER TRANSPORTER

Johnny Howard Marshall, 611 Eastland Ave.,
Ruston, La. 71270

Filed July 15, 1970, Ser. No. 23,973

Term of patent 14 years

Int. Cl. D6—06

U.S. Cl. D80—8

Fig. 1

Fig. 2

Fig. 3

FIG. 1 is an elevational view of a clothes hanger transporter showing my new design;

FIG. 2 is a perspective view thereof; and

FIG. 3 is a second elevational view thereof, showing the clothes hanger transporter in a second position.

The fragmentary broken line showing of clothes hangers in FIGS. 2 and 3 are for purpose of illustration.

I claim:

The ornamental design for a clothes hanger transporter, as shown and described.
